UNITED STATES PATENT OFFICE.

JOSEPH T. BISHOP, OF TOLEDO, OHIO, ASSIGNOR OF ONE-HALF TO JAMES A. PECORD,
OF TOLEDO, OHIO.

VESSEL LOCATING AND RECOVERING MEANS.

Application filed December 6, 1920. Serial No. 428,445.

To all whom it may concern:

Be it known that I, JOSEPH T. BISHOP, a citizen of the United States, and a resident of Toledo, in the county of Lucas and State of Ohio, have made an invention appertaining to Vessel Locating and Recovering Means; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to means for locating and recovering sunken vessels.

The object of the invention is the provision of simple and efficient means of this character which is attached to and carried by a vessel and has a pontoon, which upon the sinking of the vessel floats on the water surface but remains in attached relation to the vessel to facilitate the locating and attaching of a hoisting cable thereto. A further object of the invention is to provide the pontoon with a signal means which is inoperative except when the pontoon is floating on the water in separated relation to the associated vessel.

30 The invention is fully described in the following specification, and while, in its broader aspect, it is capable of embodiment in numerous forms, a preferred embodiment thereof is illustrated in the accompanying drawings, in which,—

Fig. 1 is a fragmentary sectional elevation of a vessel equipped with my invention, with parts broken away. Fig. 2 is a different fragmentary sectional elevation of a vessel equipped with the invention. Fig. 3 is an enlarged fragmentary view of the pontoon member with parts broken away to illustrate a portion of the electric signal means. Fig. 4 is an enlarged sectional detail of the automatic make-and-break switch of the signal means. Fig. 5 is a sectional detail of the main float operated switch of the signal means. Fig. 6 is a side elevation of a brake band and its tension means employed in connection with one of the windlass drums. Fig. 7 is a central longitudinal section of the grapple means in connection with the grapple member of a sunken vessel with said member partly broken away,

and Fig. 8 is a side elevation of the grapple means shown in Fig. 7.

Referring to the drawings, 1 designates the hull of a vessel on the deck 2 of which, at one side thereof or in any other suitable position, is fixedly mounted a pair of standards 3 having the upper end thereof forked in U-shape to provide chairs for receiving and supporting a pontoon 4. The pontoon is provided with suitable guides for slidingly receiving the side arms of the supports 6 so that upon a sinking of the vessel the standards 4 may lower from engagement with the pontoon when the latter has lowered into floating contact with the water.

The pontoon is provided in a compartment 5 thereof, which is preferably centrally located, with a windlass drum 6 having one end of a cable 7 attached thereto and wound thereon. The drum shaft carries a gear 8, which is in mesh with and driven by a gear 9 journaled in a bearing 10 in the upper portion of the pontoon and connected by a set of gears 11 to an operating crank 12 located without an upright portion 13 on the top of the pontoon. A brake wheel fixed to an end of the drum 6 is engaged by a friction brake band 14, one end of which is fixed while the other is connected to a tension lever 15, which is attached to and has its holding tension regulated by a bolt 16 and tension spring 17.

The outer end of the cable 7 with respect to the drum 6 extends downward therefrom through an opening in the deck and winds on a drum 18, which is mounted within the hold of the vessel in suitable brackets or bearing means 19 attached to the interior of the vessel. This drum is preferably larger than the drum 6 and may be manually turned by means of a crank 20 on the shaft on which is a pinion 21 in mesh with a gear 22 on the drum shaft. The turning of the drum 18 is regulated by a friction brake means, the band 23 of which is adjustable to regulate its tension the same as described in connection with the brake band 14. The cable 7 passes freely through a grapple member 24, which is attached to the vessel in the present instance for free swivel movements relative thereto. The anchoring means for the grapple member is designated 25 and may be braced and strengthened with respect to the vessel by tie rods 26 or in any

other suitable manner. The upper end portion of the member 24 is formed with a downwardly and outwardly tapering head 27 having a flange 28 at its lower edge with which a set of grappling hooks may be engaged as hereinafter described.

The grappling means comprises a slide block 29 adapted to be mounted for longitudinal sliding movements on the cable 7 between the drum 6 and grappling member 24, as shown in Figs. 7 and 8, the block being carried by a hoisting cable 30, which may be paid out from any suitable hoisting means located above the vessel. The block 29 is provided with a plurality of grapple hooks 31, three in number in the present instance, which are pivoted adjacent to the lower end of the block and have their lower ends hooked and in position to straddle and engage under the flanged head 27 of the member 24 when lowered into engagement therewith. The hooks 31 have upwardly extending arms adapted to lie in grooves 32 along the sides of the block 29 when the hooks are in released position. A spring 33 acts on each arm 31 to normally retain the hook in grapple head engaging position. The hooks may be retained in open position, with the upper arms thereof lying in the recesses 32, by a holding ring 34, which is carried by the block 29 for limited movements longitudinally thereof and is adapted to engage over the upper ends of the hook arms when the block 29 has been lowered into grapple head engaging position. A collar or plate 35 is carried below the block 29 by one or more rods 36 projecting down through the block and when the block has lowered into grapple head engaging position, the plate 35 and rod 36 are moved upward by reason of the engagement of the grapple head with the plate, thereby causing a lifting of the collar 34 by the raising movement of the rod, the collar 34 having a finger 37 projecting inward therefrom into register with the rod. The pontoon 4 is provided with an electric signal lamp 38 which is in circuit, through wires 39, with a storage battery 40 located within a closed water tight compartment 41 in the pontoon (Fig. 3). One of the wires 39 has an automatic float operating switch 42 disposed therein and adapted to automatically close the signal circuit when the pontoon is in the water. This switch comprises a tubular casing 43 mounted on and rising from the bottom of the pontoon interiorly thereof and having an insulated tubular electrical conducting member 44 mounted thereon and closed at its top. A stationary switch point or member 45 connects to one side of the broken line and projects within the member 44, and a float operated switch member 46 rises within the tubular members 43 and 44 to have contact 65 with the point 45. The member 46 is elec-

trically connected to the member 44 by a guide collar 47 through which it operates, the member 44 being electrically connected to the other side of the break in the line. The rod or member 46 forming the movable switch member projects down through the bottom of the pontoon and carries a float 48 within an annular guard flange 49 secured to the under side of the pontoon bottom. The chamber within the tubular members 43 and 44 is air tight so that if any leakage of water should occur through the opening through which the member 46 passes, the compression of the air within the switch chamber will prevent the rising of water to 80 any considerable extent within the chamber.

The signal line 39 also has an interrupting switch 50 disposed therein and automatically operable by motion of the pontoon to open and close the signal circuit so that if a light is employed as a signal means it is caused to have intermittent flashing action. This switch comprises a conductor member 51 carried by an insulation strip 52 secured to the under side of the pontoon top and connected to one side of the switch operating line. A pendulum switch member 53 is suspended from the member 51 for universal swinging movements, being weighted at its lower end to facilitate such action, and when swung in different directions from normal position is adapted to make contact with an encircling ring 54 suspended from the bottom of the insulating plate 52 and having connection with the other side of the line.

In the use of my invention, the pontoon is carried by a vessel on suitable supporting means for free releasing movements relative thereto when the vessel sinks and the pontoon comes in contact with the water on which it floats. As the vessel sinks lower into the water below the floating pontoon, the cable 70 pays out preferably first from the drum 18, due to the frictional brake action thereon being less than that on the pontoon drum 6, and also due to the greater diameter of the drum 18 than the drum 6. If the vessel continues to sink after the cable on the arm 18 has all paid out, then the cable will begin to pay out from the drum 6. Upon the lowering of the pontoon into the water the switch float 48 will be raised, closing the signal circuit, and the motion imparted to the pontoon by the action of the waves will cause a rocking of the pendulum switch member 53 to make and break the signal circuit to transmit an intermittent signal, which if a light is used, is of the flash type. When it is desired to recover the sunken vessel, a grapple block 29 is lowered on the cable 7 by which it is guided to the grapple member 24 on the vessel so as to permit the grapple hooks 31 to engage under the grapple head of such member. The

cable 30 may then be hoisted to raise the sunken vessel.

I wish it understood that my invention is not limited to any specific construction, arrangement or form of the parts, as it is capable of embodiment in numerous forms without departing from the spirit of the claim.

Having thus described my invention, what 10 I claim as new, and desire to secure by Letters Patent, is,—

The combination with a vessel, of a pontoon carried thereby for free releasing move-

ments therefrom when the vessel sinks, a windlass drum carried by the pontoon, a 15 windlass drum carried by the vessel, adjustable means associated with each drum to resist a turning thereof in one direction, a cable connecting the two drums and winding on each, one drum being adapted to unwind 20 before the other upon a separation of the vessel and pontoon.

In testimony whereof, I have hereunto signed my name to this specification.

JOSEPH T. BISHOP.
